UNITED STATES PATENT OFFICE.

PHILETUS W. GATES, OF CHICAGO, ILLINOIS.

STONE BREAKER AND CRUSHER.

SPECIFICATION forming part of Letters Patent No. 279,147, dated June 12, 1883.

Application filed March 31, 1883. (No model.)

To all whom it may concern:

Be it known that I, PHILETUS W. GATES, a citizen of the United States, residing at Chicago, in the county of Cook and State of Illinois, have invented a new and useful Improvement in Stone Breakers and Crushers, of which the following is a specification.

My invention relates to a new and useful means for effecting a secure attachment of crusher-heads to their shafts, the same being very similar in its purpose and object to the invention for which I applied for a patent on the 30th day of March, 1883, differing only in the construction of some of the parts whereby the object is effected. Reference is therefore made herein to the specification of said application for a fuller understanding of the special benefits derived from the general principle of my invention.

20 In the accompanying drawings, Figure 1 is a view of my invention, showing the shaft partly in elevation and partly in section, the crusher-head being shown wholly in section. Fig. 2 is a top view of the shaft and a horizontal section of the crusher-head in the line $x x$ of Fig. 1.

A represents the shaft, and B the crusher-head. The shaft A is provided with the usual end bearings, $a^2 a^3$, from which it increases in thickness toward the middle. About the middle of the shaft A a very slightly tapered bearing, a^2 , is provided, and near the end bearing, a^3 , a similarly-tapered bearing, a^3 , of smaller diameter, is provided. Between these bearings $a^2 a^3$ a number of concentric slightly-tapered steps, $a^2 a^3 a^4$, of successively increased diameters, are turned on the shaft. By this described construction I avoid the great inclination of one taper between the end bearings and the consequent liability of the crusher-head to rise up on it during its operation, and at the same time I secure as many places for a tight fit between the crusher-head and shaft as there are steps. The bearings $a^2 a^3 a^4$ are provided with a straight groove or key-seat, a^5 , for a purpose hereinafter explained. The crusher-head B is made of very hard metal, and is provided with end bushings, $b b'$, of softer metal—such as ordinary cast-iron—corresponding in their bore with the shapes of the bearings $a^2 a^3$ of the shaft A, in order to secure a very tight fit. These end bushings, $b b'$, are inserted into the mold of the crusher-head, and there surrounded by

55 the melted metal, which, in cooling off, holds

the bushings very firmly, and they may be further confined by lugs b^4 , formed on the bushings. The space b^2 between the end bushings, $b b'$, is of larger diameter than the shaft, around which it forms an annular chamber. Grooves b^3 are provided between the end bushings, $b b'$, and the space b^2 being filled with melted zinc C, these grooves b^3 and the key-seat a^5 serve as tenons or keys and prevent independent horizontal movement of either the shaft, crusher-head, or packing.

When it becomes necessary to remove the crusher-head, this can be effected without removing the shaft with it by lifting the head upward off the shaft, and great inconvenience and labor are thus avoided.

The end bearings or bushings, $b b'$, being harder than the zinc C, which is confined between them, serve for holding the zinc C firmly in position, thus preventing the crusher-head from becoming loose at the ends and rising up on the shaft, as in some machines of ordinary construction.

One of the end bearings, $a^2 a^3$, and the corresponding bushing, b or b' , may be cylindrical without changing the nature of my invention, which is to prevent (by a tight fit) the crusher-head from slipping down on the shaft A after it has been adjusted thereon for operation.

85 What I claim as my invention, and desire to secure by Letters Patent, is—

1. In a stone breaking and crushing machine, the combination, with the shaft A, having tapered bearings for limiting downward movement, and a key-seat, of a crusher-head having soft-metal end bushings, and a packing which forms a fastening-key for preventing horizontal movement of the head independently of the shaft, substantially as and for the purpose described.

2. In a stone breaking and crushing machine, the combination of a crusher-shaft, A, having a number of very slightly tapering bearings concentrically arranged and of successively increased diameters from top to bottom, and a key-seat, a^5 , with a crusher-head, B, having end bearings, $b b'$, of soft metal, and suitable packing metal, C, forming a fastening-key, c , substantially as and for the purpose described.

PHILETUS W. GATES.
